UNITED STATES PATENT OFFICE

112,049

DESIGN FOR A BADGE OR SIMILAR ARTICLE

Jean Bareuther Swoboda, Chicago, Ill., assignor to The Delphian Society, Chicago, Ill., a corporation of Illinois

Application August 20, 1938, Serial No. 79,470

Term of patent 14 years

To all whom it may concern:

Be it known that I, Jean Bareuther Swoboda, a citizen of the United States and a resident of the city of Chicago, in the county of Cook and State of Illinois, have invented a new, original, and ornamental Design for a Badge or Similar Article, of which the following is a specification, reference being had to the accompanying drawing forming a part of the same.

On the drawing:

I claim:

The ornamental design for a badge or similar article, as shown.

JEAN BAREUTHER SWOBODA.
